OSCILLATION-TYPE LOCK

James L. Adams, Jr., Youngstown, Ohio

Application January 30, 1935, Serial No. 4,112

13 Claims. (Cl. 61—8)

The present invention relates broadly to the act of hydraulics, and to that of canal navigation, but refers more particularly to the design and operation of high lift, ultra-high economy, simple, single-chamber oscillation-type locks, provided with a long water-inertia tube or a plurality thereof, each with a quick-acting valve of the stream-line flow type interposed therein, and of which locks the following is a full, clear, and exact description.

Objects

One object of the present invention is to produce an oscillation type lock of ultra-simplified construction, and lowest possible first cost.

15 A prime object is to very greatly reduce the total number of locks required to lift vessels over a given summit elevation, between specified terminal levels, and to thereby very materially reduce the total initial cost thereof.

20 An important object is to greatly increase the possible head across each successive lock, whereby concomitant water-power development is far more readily accomplished, at equally reduced initial and operational costs.

25 An equally important object is to cut the amount of water required for lockage purposes to a previously unattainable minimum, thereby leaving a far greater percentage of the total water available to be applied remuneratively to power generation at each successive lock, or allowing full traffic on an ultra-minimum supply.

30 A supplementary object is to greatly decrease the time taken for a total given height of lockage, thereby very materially increasing the ultimate annual capacity of the canal system, and correspondingly lowering the average ton-mile costs.

35 An object of material value is to devise a rapid lockage system that will at the same time present a maximum of safety to the traffic in transit, even in the event of any likely breakages, such as might possibly occur in the valve parts or operating mechanism, and to cut the chances of any such breakage to a low minimum.

40 A further object of value is to very greatly cut the maintenance and operational costs of the total canal system concerned, by the said decrease in total number of locks and lock crews to a minimum number, this cut in working costs being reflected equally in the ton-mile costs attained for the whole system.

45 Another object attained by the use of an ultra-minimum number of locks, each of high lift, is to provide a much more open navigation channel, far freer to traffic than usual, over much longer

distances, and to make it far easier later on to alter the general depth, width, or other features of the long intervening stretches of channel, as may be required. This is especially true if the entire canal course between terminal flights of locks can be made of the mono-level type.

5 This latter disposition of canal presents the added advantage of permitting a far greater concentration of water at the lock positions, since a long summit level can usually be made to connect with a far greater drainage area than any short summit section possibly could. And any canal which has insufficient water to operate its summit section, is not of very much use over the rest of its length.

10 A vital object of my present invention is to provide an oscillatory system of the utmost simplicity of construction, in which the long water inertia tube or tubes themselves form the outside water-receiving container of the organization.

15 An essential object is to show how a plurality of inertia tubes may be utilized, without running up the total water loss too high, but with a great gain in the matter of cutting down the constructional dimensions of both tubes and valves to a 20 far more reasonable value, as compared with a single tube system.

25 Another object is to provide plural tubes which are all of the same effective length, in order to balance the water flows therethrough, and as has 30 been shown but approximately on the drawings, in order to not overlap the tubes.

35 An essential object of my invention is to provide a sectionalized lock, and more particularly one of unequal section dimensions, preferably of 1:2 ratio, so that craft of three general lengths can be efficiently handled, and without filling and/or emptying the entire length of lock except when necessary to accommodate shipping of 40 near such maximum dimension.

45 A coincident object is to make a further and very marked gain in the saving of water required, by the utilization of such a sectionalized lock.

50 An object of material importance is to provide the floor of the lock with a generally distributed curved vane structure, presenting a multiplicity of passageways therebetween which not only serve as efficient water distributing and directing means, but at the same time provide a very material portion of the total Venturi effect.

55 Another object of value is the provision of safety interlock connections for use with the sectionalized form of lock, and the intermediate gate, to prevent opening up of the main valves ex-

cept under proper water surface level and gate conditions.

An added object is the inclusion of supplementary safety gate valves, in series with the regular main valves but for emergency use only.

A prime object is to provide a general structure which for the first time combines all of the above valued objects in one simple and practical working system.

Yet other objects of value will be self-evident to anyone skilled in the art to which my invention appertains.

With all the above and yet other objects in view, I will show and describe a preferred embodiment of my invention, indicate two alternative constructions, and will explain in detail their general modes of operation.

It will be understood that these embodiments are simply illustrative of my invention, and not as limiting the same, and that reasonable modifications of the structures shown, and their modes of operation, may be made without departing from the true spirit of said invention, or the scope of my broader claims.

25 Drawings

In the drawings, Figure 1 is a longitudino-vertical section on line I—I of Figure 2, and indicating my ultra-simple, single-tube lock system.

30 Figure 1A is a similar section of an alternative construction, showing a portion of a single lock and single Venturi bell system, provided with three inertia tubes.

Figure 2 is a plan view of the system shown in Figure 1.

Figure 3 is an offset transverse-vertical section of the same and taken on the line III—III of Figure 1, looking with the arrows.

Figures 4, and 4A, represent successive part sections taken along the same line as Figure 1, with certain vane additions in the case of Figure 4, as well as a sub-divided venturi.

Figure 5 is a longitudino-vertical section of my preferred three-tube and sectionalized single-lock system, more or less along the general line V—V of Figure 6.

Figure 6 is a plan view of my three-tube system, and showing the tubes in their proper horizontal positions, in order to clear the canal.

50 Figure 7 is a vertical transverse section of said three-tube system, taken on the line VII—VII of Figure 5, looking with the arrows.

Figures 8, 8A, and 8B show successive sectional portions of more or less the same three tube lock system as Figure 5, but with a distributing vane section added in the case of Figure 8.

Figures 9 and 10 show alternative transverse vertical cross-sections of my lock chamber, either of which might be applied to the systems of Figure 4, or of Figure 8, but these sections have been indicated as taken on the lines IX—IX, and X—X, of Figures 4 and 8, respectively, looking with the arrows.

Figure 11 is a diagrammatic representation of my sectionalized single lock system, showing typical safety interlock connections for the control thereof.

Note that the sectionalization referred to allows for three operative lock lengths, of 1:2:3 ratio, according to whether a section, or the full length of lock is used, but a 50%:50% sub-division may be substituted if preferred.

In all the figures identical parts are given the same part markings.

75 All motions which have just been terminated

are shown by solid arrows, while those which are next to occur are indicated by broken-line arrows.

Description

Referring now more particularly to Figure 1, I have indicated a single chamber lock at 1, connecting through the upper gate 2, and also through the by-pass duct 2a and valve 2b, with the high level reservoir outlet or canal 3, while at its lower level this lock connects by means of its lower gate 4, and tunnel or open cut section 5, and also by means of the by-pass duct 5a and valve 5b, with the lower canal or waterway 6, it being noted that substantially the entire bottom of said lock connects with the large end of the Venturi bell, the small end of which connects through the quick-acting and substantially stream-line flow valve 8, with the lock end of the very long fluid-inertia tube 9 of restricted area, which is preferably placed about as shown, at an easy slope upward away from the lock. The extreme outer end 10 rises to a height such that the water contained therein may, at the end of its upward swing, more or less attain the elevation of that in the upper canal 3, although such maximum height of swing is usually set at say about two feet or so under that of the canal 3 water surface for a lock of about 60 feet lift, or around 6 to 8 feet thereunder for a lock of 120 feet lift, so that make-up water to compensate for the loss-of-head due to friction may be introduced from said canal, while the water is at the said upward end of swing, as during the period when the lock is standing idle.

For a good design, the normal loss-of-head at the above lifts, will be about half the amounts above mentioned, the excess being provided to allow for a material amount of over-compensation.

If the latter is made just right, the next succeeding swing can be made to bring the water in the lock precisely to that in the connecting canals outside, thereby obviating the usual loss-of-time for further equalization of levels after the swing. The tube 9 is here used not only as an inertia tube, but also as a fluid receiver means of the utmost simplicity of structure, since one set of concrete forms may be used to produce both the required inertia tube and the water receiver.

The upper extreme end of the tube acts not only as a fluid-receiving means, but contributes a very fair inertia effect as well, so that the material of the tube is here utilized to very good advantage.

In order to make the necessary additions of "make-up" water at upper end of swing in the tube 9, a water duct is shown at 11, provided with a valve 12. This duct connects the upper canal 3, or an equivalent source of supply, with a point above the main valve 8 in the inertia tube 9.

Any necessary final equalization of levels inside and out of the lock can be carried out by means of the by-pass duct 2a and its valve 2b, at the upper level.

The lock being now again idle, and at its upper water level, I preferably make use of this idle time to waste some of the water in inertia tube 9, into the lower canal 6, by use of the duct 11a and its valve 12a, which shunt lock 1 and the main valve 8, and which water was then standing at its lower-end-of-swing, but still several feet in elevation above that in canal 6.

This will pre-compensate for loss-of-head due to friction in the next or downward swing to follow.

Note that the "rise-and-fall" section of tube 9 has a definitely determinable slope, but that

portions lying between this and the Venturi bell section may in some cases not lie in the same straight line.

Interposed between the bottom of said lock 1, and the large top end of the Venturi bell 7, I have indicated a narrow horizontal zone 13.

In Figure 1A, an alternative construction utilizing triple tubes 9a, 9b, and 9c, has been shown, instead of the single tube 9, as was shown before.

In Figures 2 and 3 no new elements appear or require identification, except the upper gate withdrawing recess R of Figure 2.

Referring now to Figures 4 and 4A, the latter being in effect a continuation of the former but with a certain intervening section missing, there are found as new parts not previously identified, the crescent-shaped vanes 17, forming a multiplicity of fluid directing passages therebetween as at 18, and which may or may not be provided to fill the zone 13, previously referred to under Figure 1.

As shown, it will be observed that these passages may be made to have a very decided Venturi effect, with generally upward divergence, in addition to their other concomitant actions of giving an upward trend to the flow, and a substantially uniform distribution thereof over the entire bottom area of the lock.

In Figure 4, in addition to the main valve 3, which is shown diagrammatically (since the general construction thereof has been indicated in detail in my co-pending valve applications Serial Numbers 701,456, filed December 8, 1933, and 742,945, filed September 6, 1934), I have shown the quick-closing emergency gate valve 19, which may or may not be provided, this gate being operated by the rack 20, slidably mounted in the bracket 21, and in operative contact with the gear 22, carried integrally with the pinion 23, on a shaft 24 common thereto, with the said pinion meshing with the 90° motion gear 25, carrying the crank-pin 26, which connects by means of the rod 27, with pin 28, on the 180° motion gear 29, meshing in turn with small pinion on the motor 30, with all these geared parts suitably mounted in operative relation upon the common stationary base 31. By-passing both the main valve 3 and emergency valve 19, I have shown the water conduit 32, and valve 33, while as an alternative construction there is shown the shorter conduit 32a with valve 33a, by-passing the emergency valve 19 only.

Beyond the two outlets of the conduit 32, I preferably place the long, inclined, grids 34, to protect the valves from detritus. At the foot of the screening grids 34, I have placed the catch-all trenches 35, which would be made to obstruct the flow as little as possible.

At bottom of the upper gate 2 there is indicated a blow-off duct 36, flushable by the water jet 37 located at one end of the lock gate, and provided for the occasional cleaning out of sand, etc., from the gate trench.

In Figure 4, a wall 7a divides the Venturi bell into two sections 7b and 7c.

In Figure 4 also, I have again shown the upper level of liquid swing within the inertia tube 9 as just below the surface elevation of the upper canal 3 leading to the lock 1, but this elevation is subject to some modification by proper design.

Turning now to Figure 5, and in addition to parts already described, there are shown the intermediate gate 38, of the substantially floated type, buoyed by the hollow flotation bulb 39, and preferably with said gate arranged for horizontal

withdrawal into the side wall of the lock 1, which wall is also provided with the narrow projecting partitions P, of more or less triangular form as will be indicated later, and which serve to keep all shipping to the central portion or well of the lock, as better shown on a subsequent figure. Below the lock 1, I have shown the now sub-divided Venturi structure 40, 41, 42, separated into sections by the heavy reinforced concrete walls 43, 44, of which the former only is provided with a gate seal at 45, arranged to contact with the lower edge of the gate 38, after the latter has been run in into position within the lock chamber, and then lowered slightly by allowing some water to enter the bulb 39, by well known means, (not shown).

Instead of the single inertia tube 9 previously mentioned, this alternative and preferred construction shows three of the latter at 46, 47, 48, all similar to said tube 9, but of about half its diameter only, while three smaller main valves 49, 50, 51, now replace the previously described and much larger single valve 3, and three similarly smaller emergency valves 52, 53, 54, now replace the larger valve 19, of Figure 4.

In order to clearly show the three tubes of Figure 5, they have arbitrarily been placed in a single vertical plane.

Theoretically, four tubes of half diameter should be used to replace one of a given larger diameter, but the three permit the use of a subdivided lock, by which very material additional water savings may be attained, so that in effect one of the four theoretically equivalent tubes may be dropped out, so far as equivalent total water volume losses are concerned. The tube lengths would be made precisely equal. The tubes may be of concrete, plain or re-enforced, or in some cases cut in massive rock.

In Figures 6 and 7 no new parts appear which require identification, other than the intermediate gate receiving recess R_a of Figure 6, and in view of the descriptions given in connection with Figures 4 and 5, it is believed that nothing further need be said as to Figures 8, 8A, and 8B, except to note that on this alternative construction, I have shown in Figure 8 wire protective screens 55, 56, and a counter-weight 57 and appropriate mounting, for the lower lift gate 4.

On Figure 8 there is also found the by-pass duct 38a, and valve 38b, below gate 38.

It will be noted that all the inertia tubes are preferably to be made as nearly a straight-line construction as possible, or with very large radius hydraulic bends.

The means for getting the intermediate gate 38 into and out of the lock has not been shown.

In Figure 8, both the intermediate and the upper gate have been shown as of the horizontally removable type, while the lower gate 4 has been indicated as of the lift type, as will be more plainly brought out in a later figure, but these designs are tentative only, for the purposes of this presentation, and may be modified.

Note that air may be forced into the bulb 39, of intermediate gate 38, (and similar expedient applied to the upper gate 2,) to eject water therefrom and float the gate 38 off of its seal 45 entirely, before shifting it out of the lock, whereby wear on the sealing means is greatly minimized.

Turning to Figure 9, a substantially vertical-wall type of lock has been shown, which gives high economy in the use of water, but which for very high lifts involves the use of extremely

massive concrete or masonry retaining walls 59, 60, which add considerably to the total lock construction cost. In this figure, the gate 4 has been indicated as of the screw-lift type, with screws 61, 62, these being mounted preferably in rotatable eccentric bushings at the bearing positions (not shown), so that the gate may be made to recede an inch or two away from the lock wall before lifting, and thus entirely clear its rubber gaskets from contact with the machined seat (not shown), before rotating the gears 63, which actuate the said lifting screws.

This is to avoid wear on the gaskets, the general form of which may be observed by referring 15 to my co-pending application on Canal locks, Serial #700,650, filed December 2, 1933.

In Figure 10, an alternative and very much lighter type of lock retaining walls 64, 65, has been indicated, which may be made with a considerable outward slope to more or less fully 20 counteract the direct thrust of the surrounding earth fill, and all at ultra-low cost, but with the inherent disadvantage of a somewhat accentuated volume of water lost through friction head 25 developed during each swing of the fluid.

The choice between the Figure 9 and Figure 10 constructions will therefore be dictated by the respective necessities of lowered water use, or lowered first cost.

30 The general disposition of the distributing vane zone 13, with its multiplicity of curved vanes 17, is clearly brought out in these two figures. These heavy reenforced concrete vanes also serve as an efficient means for holding apart, against the 35 inward thrust of the earth, the lower elements of the main retaining walls 59, 60, and 64, 65, in the respective figures here shown.

In Figure 10, occasional light triangular wing partitions are indicated at P, the longitudinal 40 spacing of which I have provisionally shown on Figures 5, 6, and 8, and the purpose of which is to restrict all traffic to the central vertical well of the lock.

In Figure 11, the intermediate gate 38 of lock 45 has arbitrarily been shown as if of the drop type, which moves downward to clear the lock, this change being made in order to be able to better show the action of the interlock contacts 66, and 67, co-acting therewith, as all the motions are 50 then reduced to a single plane.

Of these two contact elements, 66 is shown as closed by the complete rise of the gate 38, while 67 is open under these conditions, and is only closed by the action of its closing weight 68 when 55 this gate has been completely withdrawn downward, away from the lock. All the remaining interlock contacts 69, 70, in the smaller or "A" section of the lock, and 71, 72, 73, in the larger or "B" section to the right, are of the float or "F" type, such that 69, 71, 72 close just before the 60 water in the lock reaches its upper or "U" level, while 70, and 73 close just before attainment of the "L" or lower level, and open again just after this is receded from again by a few inches.

65 For valving purposes only, the "B" section of the lock is again sub-divided into the smaller, and preferably equal "B₁" and "B₂" sections, as was indicated in Figure 8.

Suitably located in a lock control house, (not 70 shown), overlooking the entire structure, there is mounted the double-pole, double-throw, or D. P.—D. T. selector switch 74, having the designated "A" and "B" sides, and the upper or "u", and down or "d" throws, matching the lock layout.

75 On its right I have shown also the single-pole,

four-throw, or S. P.—4 T. selector switch, which is likewise provided with "A" and "B" section markings, with the subscripts "u" and "d" added, to designate upward and downward lock movements, respectively. The double-pole or D. P. 5 switch is for operating both sections of the lock in unison, up or down; while the S. P. switch is provided for single section operations.

On one blade of each of these two switches there is provided an insulated metal clip, (not 10 shown), which closes one of the contacts 76 or 77, respectively, but only when the switch concerned is in its fully "open" or "off" position, as has been indicated, for example, in the case of the S. P. switch 75, which is shown between its main contact positions, and adjacent the contacts 77, which are assumed closed thereby.

These are safety interlock connections in each case, to prevent the setting of more than one of these switches at a time, with resultant confusion 15 of lock operations.

Below these switches are shown six primary interlock relays, numbered 78 to 83, respectively, closable by the respective closing coils 84 to 89, and adapted to be held in closed position by the 25 light retaining coils 90 to 95, respectively.

Through proper tieing-in connections, as shown, these relays function the several closing coils 96, 97, and 98, of the "A" section main contactor 99 and the "B" section main contactors 100 and 101, 30 respectively, all of which are fed from the incoming power line P. L., through the main service switch 102.

The outgoing feeders F_a, F_b, and F_{bb}, supplied by these contactors, each go to one main operating 35 valve motor in the respective inertia tubes 46, 47, 48, of Figure 8, but those for only one valve have been shown in the diagram, namely 49.

In each case, the main contactors 99, 100, and 101, individually feed a reversing contactor such 40 as that shown diagrammatically at 103, each with a closing coil 104 on its valve-opening or "O" side, a similar closing coil 105 on its valve-closing or "C" side, a centre-return spring 106, and an oil or equivalent dash-pot 107.

45 For each such reversing contactor there is provided a single-pole, double-throw, or S. P.—D. T. switch 108, having a valve-opening or "O" throw, and a valve-closing or "C" throw, for final manual supervision of the timing of the valve motions indicated, the plurality of such individual switches required for a plural tube and valve system being preferably combined into a single multi-pole, double-throw switch, for simplification of the operations, and to avoid any chances of error 50 arising here.

To the right of the switch 108, there are shown throw-limit switches 109 for the opening or "O" direction of valve motion, and 110 for the closing or "C" throw thereof, both being operated by 55 contact of their insulating roller tips with the pin 111, carried by and projecting from the gear 112, mounted on the suitably supported and rotatable shaft 113, said gear being in operative mesh with suitable small pinion on the motor 114, which has an upper brush 115, a lower brush 116, and a series coil 117, and which motor, by means of the crank-pin 118, mounted on the rotatable gear 112, the connecting-rod 119, and the pin 120, 70 drives the definite angular motion crank-arm 121, mounted on the rotatable shaft 122, carried in the bearing block 123, and which shaft in turn serves to operate one of the main valves, such for example, as that shown at 49, in Figures 5 and 8. 75

and which applies to the "A" section of the lock illustrated therein.

Upper loop 124 of Figure 11 connects with a contact making device 125, which in an actual construction is arranged to be normally closed whenever the water in a given inertia tube, with which it is connected, is substantially stationary, or is in the act of near approach to such condition, but is open whenever such water is in material motion in either direction of flow, (all as described in connection with Figure 1 of my aforementioned valve application, Serial Number 701,456).

Thus the near approach to zero velocity condition of the water in inertia tube will be announced by the signal or pilot lamp 126, located conveniently within the operator's range of vision.

Certain subsequent part numbers, from 127 to 147, inclusive, have been applied to identify certain of the connecting lines, or conductors, in the diagram of connections on Figure 11. Since the operation of the interlock circuits shown in Figure 11 will be self-evident, further description thereof will be omitted here.

The sectionalized lock offers such an opportunity for added water saving, that it is deemed entirely worth the extra electrical complication involved, all shorter craft being carried through with but a fractional fill, or emptying, of the lock.

30 Operation

In the operation of my single tube lock system as shown in Figure 1, starting with the water levels as indicated, any traffic to go up is entered at the lower gate 4, the latter is closed, it being assumed that during the previous period of rest, valve 12 has been opened up for a sufficient time to add make-up water to the tube 9 to "over-compensate" it for the succeeding swing, in which case main valve 8 is now opened up quickly, and the water content of tube 9 and Venturi bell 7 allowed to freely swing back into the lock 1, coming to a halt there at substantially the precise level of the upper canal 3.

If any mistake is made in proper equalization of these levels at any time, however, valve 2b may be opened up just long enough to correct it, after which upper gate 2 may be opened to permit egress from the lock, followed by entrance of new shipping, if present, or a wait for further loading.

If this wait is sufficient, valve 12a in duct 11a is opened up, wasting some water from the low level in tube 9, into lower canal 6, as previously outlined, to now "over-compensate" for the next swing down in the lock 1, after closure again of the upper gate 2, and said valve 12a. This swing should in turn carry the inside water surface precisely to that of the lower canal 6, after which lower gate 4 may be opened up, and also valve 12 as before, so as to get ready for the next swing upward in the lock.

It may be noted here that the loss-in-head due to friction appears to vary about as the square of the height of lift, other conditions being held constant.

In the operation of Figure 4, a substantially identical procedure is followed.

Sectionalized lock operation

In the operation of Figures 5 or 8, involving the sectionalized type of lock, switch 102 may be closed, and if the full length of lock is to be next utilized, operator turns to the D. P. switch 14, which controls both sections of the lock concomitantly, and is now thrown "up" or "down", de-

pending on which way it is desired for the lockage to occur, followed by the throwing of switch 108 to the opening or "O" side, and after a wait of 5 seconds or so to give the valves time to open up and the water column to get under way, this latter switch 5 is then thrown over to its closing or "C" position, to await the eventual automatic timing closure of the contacts 125, at the end of loop 124, as the water slows down toward zero velocity again on the completion of its swing, exciting the closing 10 coil "C" on the reversing contactor 103, again starting up the motor 114, but in reverse direction, followed immediately by the shift of crank-arm 121 to its "C" position, and the full closure of all the main valves 46, 47, and 48, since each 15 is connected with an identical closing mechanism.

If craft small enough to permit the use of the intermediate gate 38 has entered and been properly positioned in the lock, then on closure of this gate, and gates 2 and 4, if and as required, 20 and with the D. P. switch 74 open, so as to close its auxiliary contacts 76, the S. P. switch 75 may be now rotated to proper position on its "A" or "B" sides, and to an up or down point as required, after which on closing the switch 108 in 25 its opening or "O" direction, the required single lock-section valve will be found to function, provided proper water levels existed in the lock as a whole, before the gate 38 was run in.

30

Interlock connections

As long as the operator sets the intermediate gate and all switches properly, the interlock contacts will not interfere with his activities, but they are provided as a safety measure or check on his 35 actions, as will be understood without detailed explanation.

In the use of the locks of my invention, it will be observed that certain very definite advantages accrue from their ultra meagre water requirements, whereby a very small drainage-area can supply all the water necessary for a very heavy annual tonnage thru the locks.

Where the water supply is ample, certain other advantages accrue from the fact that an ultra- 45 large percentage of this water can be reserved for water-power development, at fairly high heads, corresponding with the high lifts possible with my locks.

Certain other advantages accrue from the fact 50 that a 65' lift lock, for example, will only require about 1' of "make-up" water per swing, as measured in the lock, and whereby the time consumed in the necessary "filling" by conduit is vastly reduced, as compared with locks of ordinary type. 55

It is probable that the very best system of interlock connections has not been illustrated, but it is believed that that shown is amply sufficient for the purposes intended, and the requirements of this application, and that moderate modifications thereof will still come within the scope of my broader claims.

I claim:

1. An oscillation type canal lock system, comprising a lock chamber, upper and lower gates 65 connected therewith, a Venturi bell connected large-end-to into the lower portion of the said lock chamber, a long fluid-inertia tube having an outer free end, which tube is connected to the small end of the said Venturi bell and rises toward the outer free end of the said tube, and a fluid control valve connected in the said tube.

2. An oscillation type canal lock system, comprising a lock chamber, upper and lower gates connected therewith, a waterway channel con- 75

- necting with the outer side of the upper gate, a Venturi bell connected by its large end into the bottom portion of the said lock chamber, a fluid control valve connected to the small end of the said Venturi bell, and a long fluid inertia tube having a free outer end and connected by its inner end to the said valve, the said outer end rising to a height comparable with that of the said waterway channel.
- 5 3. An oscillation type waterway lock system, comprising a lock-chamber, upper and lower gates connected therewith, a Venturi bell connected by its larger end into the bottom of said lock-chamber, a long fluid-inertia tube arranged 10 to act as a water-receiver as the water in lock is lowered, said tube being connected with the smaller end of said Venturi bell, and a water control means in said tube.
- 10 4. An oscillation type canal lock system, comprising a lock chamber, upper and lower gates connected thereto, a plurality of fluid directing and distributing vanes mounted in the bottom portion of the said lock chamber and forming a plurality of long fluid passageways therebetween, 15 a Venturi bell connected by its large end to the said passageways as a whole, a long fluid inertia tube with a "free" outer end of substantially the same diameter as the body of the tube, said tube being connected at its inner end to the small end 20 of the said Venturi bell, and a fluid control valve connected in the said tube near the Venturi end thereof.
- 20 5. An oscillation type canal lock system, as in claim 4, in which the said vanes are spaced more 25 widely apart at their lock end than at their Venturi bell end, so as to themselves form Venturi passages therebetween, to supplement the action of the said Venturi bell.
- 30 6. An oscillation type canal lock system as in claim 2, which is provided with a fluid conduit from the said waterway to the said fluid inertia tube, and a control valve placed in the said conduit to control the supply of "make-up" fluid to 35 said tube.
- 35 45 7. An oscillation type canal lock system as in claim 2, which is provided with a fluid conduit from the said fluid inertia tube to the navigation channel outside the said lower gate, and a control valve in the said conduit to control the "waste" of fluid from said tube.
- 40 50 8. An oscillation type canal lock system as in claim 2, which is provided with two fluid conduits from the said inertia tube, one extending to a point in said waterway outside the upper 45 gate, and the other to a point in the waterway outside the lower gate, with valves in each of said conduits to control the pre-compensation for 55 losses due to fluid friction in said oscillation lock system.
9. An oscillation type canal lock system, comprising a lock chamber, upper and lower gates connected therewith, a Venturi bell connected by its large end into near-bottom portions of the 5 said lock chamber, a fluid control valve connected to the smaller end of the said Venturi bell, and a plurality of long fluid inertia tubes which rise toward their outermost ends, said tubes 10 being connected to the said valve in parallel at their respective ends nearest to said lock chamber.
10. An oscillation type canal lock system, comprised of a longitudinally sectionizable lock chamber, upper and lower gates at the respective 15 longitudinal ends of said lock chamber, a removable intermediate gate, a Venturi bell connected large-end-to into the lower part of one of the lock sections produced by the insertion of the said intermediate gate, a fluid control valve connect- 20 ed to the smaller end of the said Venturi bell, power operating means attached to said valve, and a long fluid inertia tube having an elevated "free" end which acts as a water-receiver element for the said oscillation system and which 25 tube is connected at its other end to the said valve.
11. An oscillation type canal lock system as in claim 10, characterized by an interlock means operable by the entrance and withdrawal of the 30 said intermediate gate, and connections from said interlock to the power operating means on the said control valve, to control the starting of said power means.
12. An oscillation type canal lock system as in claim 10, characterized by interlock means mounted adjacent the lock-chamber and operable by changes in fluid level in the said lock section, and connections to the power operating 35 means of the said control valve, to control the 40 conditions of starting of said power means.
13. An oscillation type canal lock system, comprised of a longitudinally sectionizable lock chamber, upper and lower gates at the respective longitudinal ends of said lock chamber, a removable 45 intermediate gate, a plurality of Venturi bells, one connected large-end-to into the lower part of each of the lock sections produced by the insertion of said intermediate gate, a plurality of fluid control valves, one connected to each Venturi bell at its smaller end, a plurality of power 50 operating means for said valves and connected to each respectively, and a plurality of long fluid-inertia-tubes, each connected at one end to one of said valves, respectively, and each mounted 55 so as to rise gradually toward its outer free end.

JAMES L. ADAMS, JR.
